MACHINE FOR USE IN PAINTING SMALL
OBJECTS

Clifford A. Schacht, Huntington, Ind.

Application November 19, 1931
Serial No. 576,157

3 Claims. (Cl. 91—60)

This invention is a novel apparatus or machine for use in painting small objects, and it provides mechanism whereby a number of objects may be 5 rotatably mounted upon a movable carrier, which carrier when loaded with the objects can be placed upon a rotatable support, and as the latter is rotated the objects will be successively moved past the operative point where they can be subjected to the action of the painting devices and 10 then moved on out of the way; and when all the objects have been painted the carrier loaded with the painted objects can be removed and placed to one side to permit the objects to dry, while another carrier filled with objects to be painted can be 15 placed upon the support, so that the painting operations may be practically continuous.

The invention further provides means whereby each of the objects to be painted may be 20 rotated while passing the operative point so that all parts of the object will be conveniently presented to the painting device, enabling a rapid and smooth application of paint to all surfaces of the object.

In the accompanying drawings is illustrated 25 one practical mechanism embodying the invention and some modifications, and I will describe the invention with reference thereto to enable others to adopt and use the same; but I do not consider the invention restricted to the specific 30 constructions illustrated, and refer to the claims for the novel features of the invention and novel combination of parts for which protection is desired.

In said drawings:—

Fig. 1 is a front elevation of a painting booth containing my novel mechanism.

Fig. 2 is a side elevation thereof partly broken away.

Fig. 3 is an enlarged top plan view of the support and carrier.

Fig. 4 is an enlarged section on the line 4—4, Fig. 3.

Fig. 5 is an enlarged detail view of one of the bushings.

Fig. 6 is a detail section showing a modified form of the friction block.

Fig. 7 is a detail section of a modified form of object holder.

Fig. 8 is a detail section showing another modification.

In the machine shown, a rotatable support 1 is attached to or supported on the upper end of a vertical shaft 1s, and is provided with a hub member 1a in which the upper end of shaft 1s is 55 splined or pinned. Hub 1a rests on a bearing 1b mounted on transverse bars 2a attached to the side bars of a frame 2 of any suitable construction in which the mechanism may be supported. Preferably this frame forms a housing or booth, 60 open at its front side for ready access to the sup-

port and to facilitate the placing or removal of the carriers hereinafter referred to. The shaft 1s may be rotated by any suitable means, being preferably driven by an electric motor 1m at its lower end, as indicated in Figs. 1 and 2.

The carrier 3 is preferably of approximately the same exterior diameter as the support, and adapted to be placed upon the support 1 (see Figs. 1—3). This carrier may be made of wood for purposes of lightness or may be made of metal if preferred. As shown it is provided with transverse tie bars or spokes 3a, and handles 3b by which the carrier may be readily transported. When the carrier is annular I preferably provide the support 1 with segmental blocks 1e on its upper side which are adapted to enter between the spokes 3a of the carrier and engage the inner periphery thereof, and thus position the carrier accurately and fixedly on the support 1, so that the carrier will rotate therewith.

Preferably in the periphery of the carrier is an annular channel or groove 3c, and in the carrier adjacent the groove are a number of spaced bores or holes 3d in which the shanks or supports of the objects A to be painted may be placed as indicated in the drawings. In Figs. 4, 7 and 8 the objects are shown as sliders, or gliders, which have pins a adapted to be inserted in the legs of furniture and the like; and the pins can be slipped into the holes 3d as indicated in Figs. 4 and 9. In Figs. 4, 7 and 8 the holes 3d intersecting the rear edges of the channel 3c so that the pins can come into contact with a friction member hereinafter described as the carrier is rotated; and the pins will be rotated by frictional contact with such member and 95 rotate the objects as they pass the painting point.

As shown in Figs. 1—4, the friction member 100 comprises a block 4 which is supported on a bar 2f adjacent the table. This block has a projection 4a, on its side adjacent the carrier, which is curved corresponding to the periphery of the carrier 3 and is adapted to project into the channel 3c therein and contact with the shanks or pins a of the objects mounted on the carrier. The block 4 is yieldingly pressed inward by means of coiled springs 4c and is guided by means of bolts 4d extending through slots in the block and tapped into a plate 4e bolted to the bar 2f as shown in Fig. 4. The inner edge of the flange 4a is preferably provided with a frictional facing 4f of rubber, wood, or other suitable material to enhance the frictional contact with the metal shanks a of the objects and the friction block.

The objects A are made of different sizes and 115 their pins a of different diameters, according to the size of the object; and in order to hold different sized pins a properly in the carrier I provide removable interchangeable bushings, as 3s (Fig. 5), which can be inserted in the holes 3d in 120

the carrier. These bushings are non-rotatable and are provided with bores of different diameters to suit the different diameters of pins *a*. The bushings are also provided with transverse notches *3t* in their front sides which correspond to and are adapted to register with the channel *3a* when the bushings are inserted in place (see Figs. 4 and 6), so that the friction members will readily contact with the pins in the bushings as the latter are moved therewith.

Instead of making the friction block of rubber or wood as in Fig. 4, it could be made of metal as indicated at *4x* in Fig. 6, the operation and construction of the parts being obvious from the illustration in the drawings.

While the invention as shown is primarily adapted for use with objects such as *A*, it is obviously adapted for use with other objects, and therefore, instead of having holes in the carrier as above described, the carrier might be provided with a number of brackets as 5 (Fig. 7) attached to its rim by bolts *5a* or other suitable fastenings; each bracket having a groove or channel *5c* in its outer surface for the reception of the projecting lip of the friction block, and the pins of the articles above described might be inserted through the openings in the top and bottom of this channel.

In the construction shown in Fig. 7 a rotatable stub shaft *5d* is journaled in the bracket 5 and supported on the bracket 5 by a collar *5e*, and on the upper end of the shaft *5d* is a socket member *5f* in which may be placed a holder *5g* of any suitable kind adapted to support an object to be painted. In the example shown an object *A* is shown as mounted thereon, but this is merely illustrative and not limiting, and the holder *5f* could be readily made to support an article of any shape which it is desired to paint.

On the lower end of shaft *5d* may be fastened a friction disk or pinion. In Fig. 7 a disk *5r* is shown adapted to engage the friction member *4x* as the carrier is rotated, in the manner above described, to cause the object to rotate as it passes the painting point. Instead of a disk a gear *5s* might be used, as in Fig. 8, such gear meshing with a rack *4s* on the yieldable member *4t* which otherwise corresponds with the friction member shown in Fig. 6.

In the construction shown in Fig. 8 the holder *5f* may carry a head *5k* of rubber or other suitable material which is adapted to enter a socket in the bottom of the object to be treated. Obviously as stated the heads *5g* or *5k* may be shaped to engage and hold the particular kind of object to be painted.

In some cases it may be desirable to warm the objects or heat them prior to the painting operation, and for this purpose the support 1 may be housed as indicated as *H* in Figs. 1 and 2, said housing having an opening in its front through which the support and carrier partially project, this housing being provided with a door *D* which can be readily opened to permit the placing or removal of the carriers, and which may be provided with openings *d* at the points where during the rotation of the carrier the articles would have to pass through the door when the latter is closed. In this way after the carrier is placed on the support the objects can be left in the housing long enough to be heated before the painting begins;

and the objects can be partially dried in the housing after the painting operation.

Operation

Preferably a number of carriers are provided, each adapted to carry a number of the objects to be painted. After a carrier is loaded with the objects to be painted it is placed upon the support, and as the latter rotates an operator standing at the front of the booth paints the objects, preferably by means of a spray gun, and as the objects are rotated on their own axes as they pass the operator all points of the objects are presented to the operator for painting without his having to handle them. After all the objects on the carrier have been painted, the carrier containing the painted objects can be removed and set aside with the painted objects until they have dried; and another carrier with unpainted objects placed in position on the support, and the objects painted as described.

The time required for painting an object with this machine is very short, and with a sufficient number of carriers one operator, and an assistant to load the carriers place them on the support and remove them when they are painted, can paint a large number of articles in a very short time.

I claim:

1. In a machine for painting objects; a rotatable support, means for rotating said support, a carrier adapted to be detachably mounted upon said support and bodily removable therefrom; said carrier being also adapted to carry a plurality of spaced objects arranged in an annular series thereon adjacent its periphery, and means for axially rotating the objects mounted upon the carrier as they move thereby past the paint applying point, said carrier being bodily removable from the support with all the objects thereon after completion of the painting operation, the support having spaced segmental blocks on its upper side, and the carrier having intersecting spoke members extending between the ends of adjacent blocks.

2. In mechanism for painting objects of the character specified, a rotatable support, a carrier removably mounted upon said support, said carrier having a peripheral groove and an annular series of spaced holes adjacent its periphery perpendicular to and partially intersecting said groove adapted to receive object supporting stems, and a yieldable member mounted adjacent the periphery of the carrier upon the support and adapted to cause the individual objects to axially rotate as they are moved therewith by the carrier.

3. In mechanism for painting objects of the character specified, a rotatable support, an annular carrier adapted to be movably and detachably mounted upon said support, said carrier having a peripheral groove, and an annular series of spaced holes in the carrier arranged adjacent its periphery and perpendicular to and partially intersecting the groove; object supporting members mounted in said holes, and means adjacent the periphery of the carrier upon the support and adapted to engage the individual object supports as they are moved therewith by the carrier and cause them to axially rotate on the carrier.

CLIFFORD A. SCHACHT, [L.S.]
